HAND SUPPORTED ELECTRICAL MASSAGER

Samuel L. McNair, Overland Park, Kans., assignor to
Dazey Products Co., Kansas City, Mo.

Filed Oct. 24, 1973, Ser. No. 409,280

Term of patent 14 years

Int. Cl. D28—03; D24—99

U.S. Cl. D83—1 T

Fig. 1.

Fig. 2.

Fig. 3.

Fig. 4.

FIG. 1 is a top plan view of a hand mounted electrical massager showing my new design;

FIG. 2 is a side elevational view of same, the other side being substantially the same in appearance;

FIG. 3 is an end elevational view taken from the left hand end of FIG. 2, the other end view being substantially the same in appearance; and

FIG. 4 is a bottom plan view of same.

I claim:

The ornamental design for a hand supported electrical massager, as shown and described.
